THERAPEUTICAL HEATING DEVICE

Thomas J. Cross, Fort Worth, Tex.

Application June 20, 1939, Serial No. 280,067

6 Claims. (Cl. 128—401)

This invention relates to therapeutical equipment and has particular reference to a device for applying heat to the genito-urinary organs of the body for the treatment of certain pathological conditions such as gonorrhea, endometritis, salpingitis, ulcerative cervicitis, and the like in females, as well as prostatitis in males.

The primary object of the invention is to provide, in a device of this character, a means for circulating heat in close proximity with affected parts of the genito-urinary and contiguous organs.

Another object of the invention is to provide a flexible guide means whereby the expansible tubing of the device may be inserted into body cavities with little or no difficulty.

These and other objects will readily be appreciated from the following description of the accompanying drawing, wherein—

Figure 1 is a diagrammatical view of the genital region of a female body, showing the invention partially expanded and in operative position.

Figure 2 is a plan view of the invention showing part of the expansible tubing in fragmentary section.

Figure 3 is a side elevational view of Figure 2. Figure 4 is a vertical sectional view taken on lines 4—4 of Figure 3, and

Figure 5 is a vertical sectional view taken on lines 5—5 of Figure 2.

Continuing with a more detailed description of the drawing, the numeral 1 generally designates a cylindrical body or frame unit which is divided by a partition 2 into an inlet chamber 3 and an outlet chamber 4. In the form of the invention shown, each chamber 3 and 4 has projecting tubular appendages 5 and 6, all of which extend from the unit 1 in substantially the same direction, as shown in Figures 2, 3, 4 and 5. The inlet chamber 3 has an inlet tube 7 in the wall thereof, and similarly, the outlet chamber 4 is provided with an outlet tube 8, as shown in Figure 2. The ends of the chambers 3 and 4 are closed by upper and lower caps 9 and 10.

Around the outer ends of the appendages 5 and 6 there are positioned resilient collars 11 in the manner illustrated in Figures 2 and 5. These collars provide connections for the ends of upper and lower expansible tubes 12 and 13 which extend from the appendages 5 of the inlet chamber 3 to the appendages 6 of the outlet chamber 4. Retaining means, such as rubber bands (not shown) may be used to seal the ends of the tubes 12 and 13 about the collars 11.

Within each of the appendages 5 and 6 there is brazed, or otherwise secured, a guide holder 14

which extends outwardly into the tubes 12 and 13, as particularly illustrated in Figures 2 and 5. Extending through the expansible tubes 12 and 13 there are positioned flexible upper and lower guides 15 and 16 which are attached to the outer ends a of the holder 14, as shown in Figure 5. The guides 15 and 16, which may be of relatively thick tubing or of solid material, and, when connected and arranged in this manner, form elongated loops which make possible the positioning 10 of the separate tubes 12 and 13 on opposite sides of a projecting part within the body, as shown in Figure 1.

In operation, the guides 15 and 16 and the expansible tubes 12 and 13 are inserted into the 15 body orifice which opens nearest the affected part. The inlet tube 7 of the chamber 3 is connected by means of a flexible tube 17 to a source of hot water, or other heated liquid, which is of predetermined temperature. The water is then 20 conducted through the inlet chamber 3 where it divides under hydrostatic pressure and enters the expansible tubes 12 and 13 where it expands the latter to such a limit as the walls of the body cavity will permit. Thence the water passes 25 through the outlet chamber 4 and the outlet tube 8 where it is carried off by a flexible tube 18.

Since water may be supplied at predetermined temperatures and under constant pressure, there is little or no danger of burning the patient, and, 30 by reason of the expansibility of the tubes 12 and 13, the heat will reach the area or region requiring treatment.

What I claim is:

1. In a therapeutical heating device, a looped 35 guide member, an expansible looped tube enclosing the loop of the said guide, an inlet at one end of the said tube, and an outlet at the other end of the said tube.

2. In a therapeutical heating device, a looped 40 guide member, an expansible looped tube enclosing the loop of the said guide, and inlet and outlet means for circulating heated water through the said tube.

3. In a therapeutical device, a looped guide 45 member, an expansible looped tube enclosing the said guide, an inlet and an outlet in the said tube, and means within said inlet and the said outlet for supporting the said guide.

4. In a therapeutical heating device, an inlet 50 chamber and an outlet chamber, an expansible tube connecting each of the said chambers, a flexible guide within the said tube, and guide holders attached to the said chambers and supporting the said guide.

5. A therapeutical heating device comprising an inlet chamber and an outlet chamber, expandible tubes connecting the said inlet chamber with the said outlet chamber, and a flexible guide supported within each of the said tubes.
6. A therapeutical heating device comprising an

inlet chamber and an outlet chamber, expandible tubes connecting the said inlet chamber with the said outlet chamber, flexible guides within the said tubes, and means within the said chambers for supporting the said guides.

THOMAS J. CROSS.
